UNITED STATES PATENT OFFICE.

THEODORE SCHERF, OF CLEVELAND, OHIO.

APPARATUS FOR SOFTENING PAPER.

No. 873,189.

Specification of Letters Patent.

Patented Dec. 10, 1907.

Application filed August 14, 1907. Serial No. 388,512.

To all whom it may concern:

Be it known that I, THEODORE SCHERF, a citizen of the United States, residing at Cleveland, in the county of Cuyahoga and State of Ohio, have invented certain new and useful Improvements in Apparatus for Softening Paper, of which the following is a specification, reference being had to the drawings accompanying and forming part of the same:

In numerous uses to which paper is put it is desirable that the paper be as pliable or soft as possible, consistent with the strength necessary for the given purpose. For example, paper for making bags should possess a considerable degree of pliability or softness. A bag made of such paper conforms more closely to its contents, thereby distributing the weight or pressure thereof more evenly, and its mouth can be more easily gathered or folded by the hand and can be more securely closed, as is particularly desirable where the contents are of a powdered or granular character. Paper to be wrapped around electrical conductors or other parts of electrical apparatus to insulate the same should also be soft and pliable. Such paper conforms more closely to the contour of the object to be covered, and the work of wrapping or covering can be done more easily and rapidly. Paper for the manufacture of imitation leather should also be of the same soft and pliable character to produce the most effective imitation of the natural article, both for the desired pliability and to permit the production of embossed patterns without cracking or tearing under the pressure of the embossing dies. Numerous other uses might be mentioned where paper of the character described is desirable, but those referred to are sufficient to show its wide and diversified field of utility. Practically all the papers now made, however, which possess the tensile strength necessary for their manifold uses, possess also an undesirable degree of stiffness, due chiefly to the sizing, which does not permit them to bend readily, and frequently causes them to form hard creases or folds when bent on an arc of short radius, or to become creased or wrinkled in handling. This lack of pliability is a serious drawback for many purposes for which paper is used, as already pointed out. In my prior patent, No. 860,696, issued to me July 23rd, 1907, I have described and claimed broadly an invention for softening paper and have illustrated therein an effect-

ive apparatus for the purpose. My present invention, subject of the present application, also embodies the invention of the prior patent just mentioned, but also includes numerous improved features designed to add to the efficiency of the apparatus. This improved apparatus is illustrated in the annexed drawings, in which

Figure 1 is a side view of the complete apparatus, a portion of the main frame being shown in section. Fig. 2 is a detail side view of a portion of the apparatus. Fig. 3 is a rear view, partly in vertical section, of the portion of the apparatus shown in Fig. 2; Fig. 4 is a sectional plan view of Fig. 2; Fig. 5 is a detail front view of the upper portion of Fig. 2; Fig. 6 represents a side view of an apparatus such as described in Fig. 1, with a modified arrangement of ribbing bars; Fig. 7 represents a front elevation of the ribbing bars, guide rollers, and supporting frame forming part of the apparatus shown in Fig. 1, the rear feed rollers being omitted for clearness of illustration, and Fig. 8 represents a view taken on the line 8—8 of Fig. 6 looking in the direction of the arrows.

The apparatus of my prior patent before referred to includes one or more sets of co-operating kneading or breaking rolls, intermeshing to successively greater depths, between which the paper to be softened is drawn at a higher lineal speed than the peripheral speed of the rolls. My present invention also employs such sets of rolls, and in its preferred embodiment six sets are provided, arranged in two vertical series of three roll-sets each. The actuating mechanisms for the sets, to rotate the rolls and draw the paper through them, are all substantially alike, and are connected by power transmitting devices so that power applied to one set to actuate the same will drive all the rest.

With the above brief outline in mind the following description of the apparatus illustrated in the drawings will be readily understood.

On a suitable base, A, are mounted two pairs of side frames B, B', C, C', in which are mounted the six roll-sets. The kneading or breaking rolls are designated by D, D', and as shown are bladed or fluted longitudinally. The rolls of each set are journaled one above the other in the side frames, and the upper roll D' is mounted in vertically adjustable bearings d', d'', so as to vary the extent to which the blades of the two rolls intermesh.

- Back of each set of kneading rolls is a pair of frictional feed-rollers, E, E', by which the paper under treatment is drawn positively through the kneading rolls. The bearings 5 e' , e' , of the upper feed rolls E' are loosely mounted in vertical guides in the side frames, so that the weight of the upper roller will be borne by the lower roller, to aid in producing the necessary grip on the paper between them. The shaft of the lower feed roller is 10 the driving shaft of its roll-set, (by which term is meant a pair of kneading rolls and the devices co-operating therewith), and each of said shafts is connected with the corresponding shaft in the roll-set next in the series, while one or another of these shafts is 15 suitably connected with a source of power, not shown, so that all the roll sets will be driven from a single lower feed-roller shaft.
- For the purpose of driving the kneading rolls, the following instrumentalities are provided for each roll-set. On one end of the lower feed-roller shaft is a gear e^2 , connected through a pair of gears e^3 with a gear d^2 on 20 the end of the shaft of the lower kneading roll, D, thereby driving the latter in a direction to assist the feeding of the paper between the kneading rolls. Alongside of the gear d^2 , on the same shaft, is a gear d^3 , meshing with a gear f journaled in a bracket f' on 25 the side frame. This gear f meshes with a similar gear f^2 journaled in the upper arm of a bell-crank f^3 pivotally mounted on the shaft of gear f . The other arm of the bell 30 crank has a vertically extending slot f^4 working on a set screw f^5 . The gear f^2 engages a gear d^4 on the shaft of the upper kneading roll, D'; and the gears d^3 , f , f^2 , d^4 being the same in size, it will be seen that the two 35 kneading rolls will be rotated at the same speed. These rolls might be driven one directly from the other by intermeshing gears on their shafts, but it will be remembered that the upper roll is capable of vertical adjustment. This adjustment would of course 40 make the said gears mesh to a less depth, thereby producing more or less lost motion between the two, and a loss of efficiency in transmitting power, as will be readily understood by those familiar with the principles of toothed gearing. With the arrangement shown, however, no such lost motion and loss of efficiency can occur. Thus, the mesh 45 of the gears d^3 , f and f^2 is constant, while the mesh of gears f^2 and d^4 can be adjusted or varied, as the roll D' and its gear d^4 are raised or lowered, by throwing the vertical arm of the bell crank f^3 toward or from the gear d^4 as may be necessary. When the 50 gears just referred to are in proper mesh the bell-crank is locked in its adjusted position by tightening its set screw f^5 . The lost motion which might result under the conditions referred to above would also vary the lateral 55 spacing of the intermeshing blades of the

kneading rolls, whereas the blades of one roll should be equidistant from the adjacent blades on the other as the blades come into mesh. This latter condition is clearly shown in Figs. 1 and 2; and since the meshing of gears f^2 and d^2 can be kept constant, by the proper adjustment of the former toward or from the latter when necessary, it will be seen that there can also be no variation of the lateral spacing of the blades on one kneading roll relative to the blades on the other, although the depth to which the blades intermesh can be varied as desired. This effect of the gearing described, in keeping the lateral spacing of the blades the same at all times, is in some respects more important than the saving of efficiency referred to, since variation of such spacing would make more acute the angles between the paper and the blades and would increase the friction thereon, which might result in rupture of the paper or necessitate reducing the speed at which the paper is drawn, thereby reducing the output of the apparatus.

The upper feed-roller, E', may be positively driven, as by gearing the same with the lower rollers, but they may be driven only by frictional engagement with the lower rollers through the paper passing between them. This latter method is employed in the apparatus described herein.

In front of each set of kneading rolls is a pair of idle rollers G, G', which serve to guide the paper between the former. In the case of the guide rollers in the first roll-set, that is, the roll-set at the bottom of side frames B, B', the paper is received from an idler H, which in turn receives the paper from the roll of paper I, rotatably supported in arms I' projecting forwardly from the side frames B, B'. Other idlers H', H'', H''', H''' are provided as shown, to properly support the paper at various points in its travel through the apparatus. The paper leaves the last roll set by way of an idler H'''', at the rear of the last pair of feed rollers.

In order to increase the friction between the paper and the feed-rollers and the resulting tractive effect of the latter the paper is kept in contact with the rollers over a large extent of surface of the latter, and for this purpose an idler J is provided in front of each pair of feed rollers, so that the paper will be directed down and around the lower feed-roller. At the same time, the idlers H', H'', H''', H''' and E''' are so positioned as to keep the paper in contact with the respective upper feed rollers over at least half the surface of each, as shown in Fig. 1.

To transmit power from the one roll-set to another to drive the latter from the former, the lower feed-roller shaft of each of the two sets is provided, at the end opposite to gear e^2 , with a bevel gear e^6 , meshing with bevel gears e^7 on a transmission shaft e^8 . Or the

lower shafts may be provided with sprocket wheels e^8 , connected by a chain e^9 . Both methods are illustrated; the first to connect the roll-sets of the same series, the second to connect the two series.

As previously stated, the paper is drawn through the kneading rolls faster than the peripheral speed of the rolls. This operation is secured by suitably proportioning the 10 diameters of the kneading rolls and gear d^2 , and the diameters of the feed-rollers and gear e^2 , so that with the same angular speed in both, the feed-rollers will have greater peripheral speed than the kneading rolls; or 15 by suitably proportioning the gears e^2 and d^2 ; or by both methods, as in the apparatus illustrated.

The operation of the apparatus as thus far described will be readily understood. The 20 effect of each set of kneading rolls is to bend the paper more or less sharply over the co-operating blades, first in one direction and then in the other. The natural result of such action would be to leave the paper 25 crimped or corrugated, but such a result is prevented by drawing the paper through rolls at a speed higher than that at which it would travel if carried forward only by the rolls themselves. Hence the paper is not 30 only bent over the blades in succession, but is also drawn firmly over their edges. This "slip" relative to the blades causes the line of fold over each blade to move slowly backward until the blade is by the rotation of the 35 roll carried out of contact with the paper. In the meantime the paper is engaged by succeeding blades of the two rolls, and the action just described is repeated on each blade, so that, even if but one set of rolls 40 were employed, every portion of the paper would be subjected to one or more such kneading and drawing actions. I prefer, however, to employ several sets of rolls, for example six sets, as in the apparatus illustrated. The rolls of the first set are by adjustment of the upper roll made to intermesh to a comparatively slight depth, and their effect on the paper is correspondingly less than if they meshed to a greater depth. 50 The rolls of the succeeding intermesh to successively greater depths, with correspondingly greater effect, so that the paper is gradually brought to the desired degree of softness and pliability.

55 As is well known, some papers particularly the heavier kinds, are formed by uniting two or more layers or films of pulp in the wet state. Thus united the several layers form a single, firm sheet of paper, sometimes 60 called "multi-layer paper." The action of the kneading rolls on such paper is not only to render the same pliable and soft in the manner described, but also to loosen the layers from each other at numerous points, 65 leaving them adhering at intermediate

points. This result can readily be observed by bending the paper, causing the separated portions of the layer on the inside of the bend to bulge and form blister-like protuberances. By drawing the sheet over 70 a rigid, rounded edge or bar these blisters can be folded down upon the other layer or layers and thus formed into ribs or ridges, as described more fully in my prior patent No. 860,697, issued on the same day as my patent first mentioned. By inclining one or more of the bars the ribs produced thereby will cross the ribs produced by the other. In this way various effects can be produced, as more fully explained in my prior patent 75 No. 860,697 above referred to. One of the most pleasing effects is produced by one or more bars at about 45° to the length of the paper, and one or more bars at the same angle, but inclined oppositely to the first. The 80 ribs thus produced are at right angles to each other, giving a fair imitation of alligator skin. A convenient construction for producing this effect is illustrated in Figs. 1 and 7. At the rear of the apparatus the 85 base is provided with a pair of side frames N, N', supporting respectively the V shaped members O, O', the branches of which are at right angles to each other, thus forming four ribbing bars over which the paper, after 90 leaving the idler H^0 , passes in the manner shown in Fig. 7, so that the opposite sides of the paper are operated upon successively by the ribbing bars. Rollers o, o' are journaled at the top and bottom of the side frames, 95 respectively, and guide the paper to and from the ribbing bars. From roller o' , the paper is directed into engagement with a pair of feed rollers E^2, E^3 , by which the paper is 100 drawn firmly over the ribbing bars. The feed rollers are driven from the last softening mechanism by a chain P, running on sprockets carried by the lower feed rollers.

In Figs. 6 and 8 there is shown a modification of the arrangement of the ribbing mechanism, shown in Figs. 1 and 7. Four ribbing bars are shown L, L', L^2, L^3 , arranged in different horizontal planes and supported in side frames M, M', mounted on the base A. After leaving the idler H^0 the paper passes 110 under an idle guide roller l , up over the bar L' , thence down under bar L , up past two guide rollers l', l'' , between bars L' and L^3 ; thence the paper passes over bar L^2 , down under bar L^3 , up over an idle roller l^3 , and 115 down under a guide roller l^4 by which it is directed into engagement with the feed rollers E^2, E^3 , by which the paper is drawn firmly over the ribbing bars. The feed-rollers are driven from the last softening mechanism by the chain P' running on sprockets carried by the lower feed-rollers. The ribs or ridges produced by these bars are generally parallel with one another and at right 120 angles to the length of the paper.

By providing a pair of feed rollers in conjunction with each pair of kneading rolls, I am enabled to relieve the tension on the paper between each pair of kneading rolls and the preceding set or pair of feed rollers, and am enabled to feed the paper through the apparatus at a much greater rate of speed than is the case with the apparatus shown in my Patent 860,696, above referred to.

16. The apparatus herein described can, of course, be modified greatly as to details of construction and arrangement, nor is the precise number of sets of kneading rolls material. More or less than six sets can be used, depending, in general, upon the degree of softening desired.

What I claim is:

1. In an apparatus for softening paper, in combination, coöperating kneading rolls between which the paper passes, feed rollers engaging the paper after issuance from the kneading rolls, and means for rotating the kneading rolls and the feed-rollers at different peripheral speeds, as set forth.

2. In an apparatus for softening paper, in combination coöperating kneading rolls between which the paper passes, feed-rollers engaging the paper after issuance from the kneading rolls, and means for rotating the feed-rollers at higher peripheral speed than the kneading rolls, as set forth.

3. In an apparatus for softening paper, in combination, coöperating kneading rolls between which the paper passes, feed-rollers engaging the paper after issuance from the kneading rolls, means for rotating the kneading rolls and the feed-rollers at different peripheral speeds, and means intermediate to the kneading rolls and the feed-rollers for guiding the paper into engagement with the latter, as set forth.

4. In an apparatus for softening paper, in combination, coöperating kneading rolls between which the paper passes, feed-rollers engaging the paper after issuance from the kneading rolls, means for driving the feed-rollers, and means for driving the kneading rolls from the feed-rollers, at different peripheral speed from the latter, as set forth.

5. In an apparatus for softening paper, in combination, coöperating kneading rolls between which the paper passes, feed-rollers engaging the paper after issuance from the kneading rolls, means for driving the feed-rollers, and gearing connecting the kneading rolls with the feed-rollers to drive the former at lower peripheral speed than the latter, as set forth.

6. In an apparatus for softening paper, in combination, a kneading roll, a second kneading roll coöperating with the first adjustable toward and from the same, means for driving the first roll, and gearing connecting the rolls to drive the second from the

first, including a gear adjustable toward and from the latter, as set forth.

7. In an apparatus for softening paper, in combination, a kneading roll, a second kneading roll coöperating with the first and adjustable toward and from the same, gears on the roll-shafts at adjacent ends of the same, a pair of gears in mesh with each other and with the respective gears on the roll-shafts; and means for adjusting, toward and from the gear on the shaft of the adjustable roll, the gear in mesh therewith, as set forth.

8. In an apparatus for softening paper, in combination, a kneading roll, a second kneading roll coöperating with the first and adjustable toward and from the same gear on the roll-shafts, a third gear in mesh with the gear on the first roll-shaft, a fourth gear in mesh with the third and with the gear on the shaft of the adjustable roll, and means for shifting the said fourth gear concentrically of the said third gear, as set forth.

9. In an apparatus for softening paper, in combination, a kneading roll having a gear, a second kneading roll coöperating with the first and adjustable toward and from the same, and also having a gear, a gear in mesh with the gear of the first roll, an arm pivoted concentrically with the last mentioned gear, a gear carried by said arm and adapted to be mesh with the last mentioned gear and with the gear of the adjustable roll, and means for locking said arm in adjusted position, as set forth.

10. In an apparatus for softening paper, in combination, a pair of kneading rolls having intermeshing blades, means for varying the extent of the intermeshing thereof, and means for preserving uniform lateral spacing of the intermeshing blades, as set forth.

11. In an apparatus for softening paper, in combination, a pair of kneading rolls having intermeshing blades, means for varying the extent of the intermeshing thereof, means for driving one of the rolls, and mechanism for driving the other roll therefrom and for preserving uniform lateral spacing of the intermeshing blades, as set forth.

12. In an apparatus for softening paper, in combination, a pair of coöperating kneading rolls between which the paper passes, a pair of feed-rollers engaging the paper after issuance from the kneading rolls, means for driving one of the feed-rollers, gearing intermediate to the driven feed roller and one of the kneading rolls to drive the latter from the former, and gearing intermediate to the driven kneading roll and the other kneading roll to drive the latter from the former, as set forth.

13. In an apparatus for softening paper, in combination, coöperating kneading rolls between which the paper passes, a guide roller

to direct the paper into engagement with said rolls, feed-rollers engaging the paper after issuance from the kneading rolls, a guide roller to direct the paper into engagement 5 with the feed-rollers, and means for driving the feed-rollers at higher speed than the kneading rolls, as set forth.

14. In an apparatus for softening paper, in combination, a plurality of sets of kneading rolls, sets of feed-rollers for the respective sets of kneading rolls, means for driving the kneading rolls from their respective feed-rollers, and means for driving the sets of feed-rollers one set from another, as set forth.

15. In an apparatus for softening paper, in combination, a plurality of sets of kneading rolls, arranged one set above another, sets of feed-rollers for the respective sets of kneading rolls, gearing connecting each set of feed-rollers with its respective kneading rolls, and gearing for driving the feed-roller sets one from another, as set forth.

16. In an apparatus for softening paper, in combination, a plurality of sets of kneading rolls, arranged in a plurality of vertical series, sets of feed-rollers for the respective sets of kneading rolls, means for driving the sets of kneading rolls from their respective feed-rollers, means for connecting the feed-roller sets in each series to drive the said sets one from another, and means connecting a feed-roller set of each series to transmit driving power from one series to another, as set forth.

17. In an apparatus for softening paper, in combination, a pair of spaced side frames, kneading rolls journaled therein, feed-rollers journaled in the side frames on one side of the kneading rolls, means carried by the side frames for supporting a roll of paper on the

other side of the kneading rolls, and means 40 for driving the feed-rollers at higher speed than the kneading rollers, as set forth.

18. In an apparatus for softening paper, in combination, a pair of spaced side frames, kneading rolls and feed-rollers journaled 45 therein in sets in vertical series, means for driving the said rolls and rollers, and a pair of arms extending from the side frames and adapted to support a roll of paper, as set forth.

19. In an apparatus for softening paper in combination, a plurality of ribbing bars over which the paper passes, and guide rollers for directing the paper to and from said bars, as 55 set forth.

20. In an apparatus for softening paper, in combination, a pair of spaced side frames, ribbing bars supported thereby, and guide rollers journaled in the side frames for directing the paper to and from said bars, as set 60 forth.

21. In an apparatus for softening paper, in combination, means for loosening portions of the layers of multi-layer paper, a guide roller receiving the paper after issuance from said 65 means, ribbing bars receiving the paper from said roller, and a guide roller receiving the paper from said bars, as set forth.

22. In an apparatus for softening paper, in combination, a series of reversely inclined 70 ribbing bars, a supporting frame therefor, and means for directing paper to and from said bars, as set forth.
